(57) **CLAIM**

The ornamental design for a ceiling fan blade iron, as shown and described.

DESCRIPTION

FIG. 1 is a top perspective view of a ceiling fan blade iron, showing my new design, shown in the environment of a ceiling fan;

FIG. 2 is a bottom perspective view thereof;

FIG. 3 is a front view thereof;

FIG. 4 is a rear view thereof;

FIG. 5 is a left side view thereof;

FIG. 6 is a top view thereof;

FIG. 7 is a bottom view thereof;

FIG. 8 is an enlarged view of the ceiling fan blade iron of FIG. 1;

FIG. 9 is an enlarged view of the ceiling fan blade iron of FIG. 2;

FIG. 10 is an enlarged view of the ceiling fan blade iron of FIG. 3;

FIG. 11 is an enlarged view of the ceiling fan blade iron of FIG. 4;

FIG. 12 is an enlarged view of the ceiling fan blade iron of FIG. 5;

FIG. 13 is an enlarged view of the ceiling fan blade iron of FIG. 6; and,

FIG. 14 is an enlarged view of the ceiling fan blade iron of FIG. 7.

The broken lines illustrate environmental structure and portions of the ceiling fan blade iron. None of the broken lines form part of the claimed design.
